* cited by examiner

Primary Examiner — Selina Sikder(74) *Attorney, Agent, or Firm* — Harness, Dickey & Pierce, P.L.C.(57) **CLAIM**

The ornamental design for a housing for a HVAC contactor, as shown and described.

DESCRIPTION

FIG. 1 is a perspective view of a housing for a HVAC contactor;

FIG. 2 is a front view hereof;

FIG. 3 is a back view thereof;

FIG. 4 is a right side view thereof;

FIG. 5 is a left side view thereof;

FIG. 6 is a top view thereof;

FIG. 7 is a bottom view hereof, and,

FIG. 8 is another perspective view of the housing shown in FIG. 1 with exemplary components of an HVAC contactor shown in broken lines.

The details shown in broken lines depict environmental subject matter only and form no part of the claimed design.
